TUFTED PRODUCT AND METHOD OF
MAKING SAMEJacques M. Schloss, Greensboro, N. C.
Application January 9, 1951, Serial No. 205,152

1 Claim. (Cl. 2-278)

1
This invention relates to tufted products having pile yarn stitched or woven into a fabric base, and more particularly to a tufted product in which designs are formed therein by depressing the cut or uncut pile on a sewing machine, and to a method of making the same.

The conventional way of forming designs in tufted products made with tufting machines, such as bath mats and scatter rugs, is by an "overlay" or "inlay" method. The "overlay" design is formed by taking the bath mat or scatter rug having either cut or uncut pile tufts stitched in a fabric base and passing the product through the tufting machine to add additional pile yarn on top of or as an "overlay" to the pile yarn originally inserted by the tufting machine. The "inlay" design is accomplished by leaving bare spaces in the fabric base when the tufted product is formed originally on the tufting machine and subsequently passing the product again through the tufting machine to fill in or "inlay" these bare spaces with pile yarn.

The disadvantages of the "overlay" and "inlay" methods of forming designs in tufted products are that the "overlay" method consumes considerable quantities of additional yarn, and the "inlay" method involves high labor costs in the stopping and starting of the tufting machines. Also, these methods result in a product having uneven surfaces which in bath mats and scatter rugs is undesirable.

The customary way of creating designs in woven tufted products is by using a jacquard head on the loom. The pattern or design is effected by having the pile yarn cut at varying heights. The creation of the design in this way slows down the operation of the loom to a great extent and materially increases the unit cost of the resulting tufted product.

In accordance with the present invention various designs may be provided in tufted products by taking a tufted product having a continuous pile surface formed on the tufting machine or loom and passing the tufted product through a conventional sewing machine having either one or as many needles as desired. The thread of the sewing machine depresses a portion of either the cut or uncut pile surface and holds the pile tufts in fixed relation to the fabric base. The contrast between the upstanding and depressed pile tufts forms a design having a sculptured effect. This result is obtained without using additional pile yarns and without the extensive adjustments inherent in forming designs by the "inlay" method on the tufting machines.

2
In addition to the foregoing advantages, the present invention affords greater flexibility and variety in providing tufted products with designs. The background for this advantage lies in the difference between the structure and operation of the tufting machine or loom and the sewing machine. As is well known, a tufting machine, though it can stitch in a straight or curved line, cannot make an abrupt turn in a continuous operation, and in order to accomplish an abrupt turn while producing tufted products on the tufting machine, it is necessary to stop, adjust the tufted product and start a stitching operation anew. As stated above, in order to weave designs in a woven tufted product, jacquard apparatus must be added to the loom with the resulting slow-down in the operating speed of the loom. This lack of operating flexibility is not present in the conventional sewing machine used in the present invention, and it will be readily recognized that the use of the sewing machine in forming the designs in the stitched or woven tufted product of the present invention results in a tufted product quickly produced and having unlimited design possibilities. This is true since the tufted product may be turned on the sewing machine in any direction whatsoever without disturbing the continuous operation thereof in forming designs therein.

30 The tufted product of the present invention and the method by which it is formed are described in further detail below in connection with the accompanying drawings in which:

35 Figure 1 is a plan view of a tufted product formed according to the present invention;

Figure 2 is a plan view of the reverse side of the tufted product shown in Figure 1;

Figure 3 is a transverse section taken substantially on line 3-3 in Figure 1; and

40 Figure 4 is a fragmentary transverse view illustrating a modified form of the tufted product.

Referring to Figures 1, 2 and 3 of the drawing, a tufted product designated generally by the numeral 10 is formed on a tufting machine (not shown) by inserting or stitching pile yarn 12 in a fabric base 14 to form a continuous pile surface.

The reverse side of the tufted product 10, shown in Figure 2, may be marked with pencil, crayon, stencil or any suitable means, to provide a design outline, and the tufted product 10 may then be passed through a sewing machine (not shown) to stitch a portion of the pile yarn 12 so that the depressed or stitched portion of the pile yarn 12 is held in fixed relation to the fabric base 14 as shown at 16 in Figure 3.

Naturally, the conventional sewing machine may be provided with 1, 2 or more needles, depending upon the form of design desired. The tufted product 10 was passed through a sewing machine having two needles to form the shell design shown clearly in Figure 1. This design results from the contrast between the upstanding and depressed pile yarn 12.

In Figure 4, uncut pile yarn 12' is inserted or stitched in a fabric base 14' in the same manner as the cut pile yarn 12 of the tufted product shown in Figures 1, 2 and 3 and the uncut pile 12' is depressed or stitched at 16' so that it is held in fixed relation to the fabric base 14' in the same way as the cut pile yarn 12. This view illustrates the fact that designs may be formed in accordance with the method of the present invention in tufted products having uncut pile yarn.

It will be understood that it is immaterial whether the pile surface is stitched on the tufting machine or woven on a loom since the invention of the applicant is directed to either stitched or woven tufted products in which designs are formed by sewing a portion of the cut or uncut pile, and to a method of making a tufted product having such designs formed therein. Also, it will be appreciated that the material used

in forming the tufted product is not important, whether cotton, wool, rayon or the like.

I claim:

5 A tufted rug comprising a fabric base and a pile yarn surface, a substantially small portion of said pile yarn being sewed in lines throughout a major portion of the pile yarn surface, said lines ranging in width from about 1 to 3 needles and being held in depressed, fixed relation to said fabric base so that, while the unsewed pile yarn forms a uniformly even, projecting pile yarn surface over substantially the entire area of the rug, the sewed, depressed pile yarn forms a lineal design in the pile yarn surface of the rug.

10 15 JACQUES M. SCHLOSS.
